Design No. 711.

A. J. Blanchard's Design for a Portable Grate or Fireplace.

Blanchard, Tastell & C. designers

Patented May 29, 1865.

Dec. 7/11

Abner J. Blanchard, of South Reading, Mass.

Assignor to

Blanchard, Farwell &c.

Letters Patent No. 711. Dated. May 29th 1855.

The schedule referred to in these Letters Patent, and making part of the same.

To all Persons to whom these Presents shall come,

Be it known, that I, Abner J. Blanchard, of South Reading, in the County of Essex, and State of Massachusetts, have invented or produced an ornamental design for a portable grate or fire place, such design being fully represented in the accompanying drawings.

of which - Figure 1. exhibits the design in elevation. - Figure 2. shows it in top view. - Figure. 3. is a vertical, central, and transverse section of the front plate, the blowers, base, cornice, the top plate and part of the, orn of a portable grate or fire place constructed in accordance with my design - Figure 4. is a horizontal section taken on line A.B. of Figure 1. -

I do not intend to include the feet C. C. C. in the said design, but all that which appears in Figure 1. as above said feet constitutes, in connection with what is represented, in Figures 2. 3. and 4. the design in question.

The front plate of the fire-place is represented at D. D. D.. E. E. being blowers adapted thereto and placed in front of and above the grate C. The base plate is seen at H. and the cornice or top plate at I. the said top plate being surrounded on wth K.

The composition of mouldings and the ornaments in

relief, on the front plate, base plate and cornice or top plate, and considered irrespectively of those of the feet C. I claim as new.

And I also claim the peculiar design or configuration of the urn K, and that of each of the blowers.

In testimony whereof I have hereunto set my signature this third day of April A.D. 1855.

Witnesses,
